BENJAMIN A. BAILEY, OF LEWISTON, MAINE, ASSIGNOR TO HIMSELF AND
WILLIAM H. KILVERT, OF SAME PLACE.

Letters Patent No. 80,529, dated August 4, 1868.

IMPROVEMENT IN YARN-BEAMS FOR LOOMS.

The Schedule referred to in these Letters Patent and making part of the same.

TO ALL WHOM IT MAY CONCERN:

Be it known that I, BENJAMIN A. BAILEY, of Lewiston, in the county of Androscoggin, and State of Maine, have invented an Improvement in Yarn-Beams; and I do hereby declare that the following, taken in connection with the drawings which accompany and form part of this specification, is a description of my invention sufficient to enable those skilled in the art to practise it.

The invention relates to the construction of yarn-beams for looms, with particular reference to making such beams adjustable in length; to adapt them to weaving of different width of goods upon the same loom.

As beams are now constructed for different widths of work, they are furnished with auxiliary heads clamped around the beam, inside of the main or fixed heads, and the use of these false heads makes the beams very heavy and expensive; and the object of my invention has been to so construct the beams, that the main heads should themselves be movable, to increase or diminish the length of the beam, the means of adjustment being such that the heads may be firmly fastened upon the beam at any desirable points.

My invention consists in a beam, made with movable heads, having provision for adjustment and confinement, in accordance with the length of beam required, or the width of goods to be woven.

The drawings represent a yarn-beam, embodying my improvement.

A represents one end of the beam, in elevation, and B the opposite end, in section.

C is an end view of the beam.

a denotes the beam-barrel or cylinder, upon which the yarn is wound.

c c denote the two heads.

d d, the beam-shaft or gudgeons.

Each head, c, is made with a boss, e, in which are mortises f, for the reception of metal keys g, as seen at B. Corresponding with these keys, I form in the surface of the roll or barrel a, mortises, for reception of metal key-seats h, each seat being permanently secured to the beam by screws i, or other suitable fastenings.

The outer surface of each key-seat is made with a series of serrations, and the surface of the key bearing against such seat is correspondingly serrated, as seen at B. Each key, g, has a shoulder, k, abutting against the end of the boss e, and the key is held against its seat by a set-screw, l, the serrations of the key interlocking with those of the key-seat, and preventing end-movement of the head. By starting back the screws, the keys are loosened, so that the keys, and, with them, the head may be slipped inwardly or outwardly on the beam, to adjust the heads in accordance with the length of beam desired, the heads being secured to the beam by pressing the keys down to their seats (by the set-screws) in any position within the length of the seats.

The same method of securing the heads in position may be used with stationary heads, or with a beam of fixed length, that is to say, by employing the serrated keys, in connection with corresponding key-seats, these devices not only holding the heads firmly in position when the beam is in use, but enabling them to be readily and easily "trued" upon the beam. As the abutting-surfaces of the key and key-seats are made straight transversely, and as each key sets in the mortise in the boss, and the set-screw holds it down to the key-seat, it will be obvious that this construction secures the head from rotation as well as from endwise movement.

1. I claim the serrated keys and key-seats, for holding the head in position, substantially as set forth.
2. I also claim a yarn-beam, having main heads, made movable and adjustable, in combination with serrated key-seats and adjustable keys, substantially as described.

BENJAMIN A. BAILEY.
